UNITED STATES PATENT OFFICE.

GEORGE W. JOHNSTON, OF ST. JOSEPH, MISSOURI.

AIR AND VACUUM MOTOR.

No. 827,021.

Specification of Letters Patent.

Patented July 24, 1906.

Application filed January 23, 1904. Serial No. 190,804.

To all whom it may concern:

Be it known that I, GEORGE W. JOHNSTON, a citizen of the United States, residing at St. Joseph, in the county of Buchanan and State 5 of Missouri, have invented certain new and useful Improvements in Air and Vacuum Motors; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 My invention relates to an improved system of motive power for railway-cars and other vehicles; and the object of my invention is to provide a device which after receiving a suitable initial charge of compressed 20 air may be propelled with great power at a minimum expense for long distances and at maximum speed.

25 I attain my object by the use of pumps, tanks, and connecting mechanism carried by the car or vehicle, as illustrated in the accompanying drawings, in which—

Figure 1 is an elevation of a car or vehicle, one side broken away at the front, showing a vertical section of the front wheel on the farther side, which is provided with a pump with 30 rotary operating mechanism, and also showing the rear wheel on the near side, which contains one of the engines, and the tanks and connecting mechanism. Fig. 2 is a plan of the entire device. Fig. 3 is a detail section 35 view of a cylinder, piston, cross-arms, and rollers and inlet and outlet ducts of an air and vapor engine in a wheel. Fig. 4 is a side view of a cam, showing segments of circles 40 that operate a cut-off valve; and Fig. 5 is a longitudinal section of a pump and its connection with the platform of a car.

Similar letters refer to similar parts throughout the several views.

45 In the construction of my device D D are the vacuum-tanks, and d d are pipes forming connection between said tanks, rendering the tanks practically one. Wheels A A are provided with reciprocating pumps having a rotary operating mechanism upon which I obtained Letters Patent January 6, 1903; No. 717,750. By means of these rotary pumps the air is taken from tanks D D through 50 pipes D' D', thence through a hollow stationary axle E, thence through pipe F and lever-valve f into pipes F' F', and thence through

connecting-pipes F' F' into high-pressure tanks G G. In Fig. 2 valve f is shown open.

I I are automatic pumps set vertically at both ends of vehicle, which are adapted to 60 take air from said vacuum-tanks D D through pipes I' I' and to force air through pipes J J into high-pressure tanks G G. Said pumps I I are automatic and actuated by the motion of frame Q up and down on the springs, the 65 piston-rods of said pumps being attached to said frame.

K is an automatic pump, preferably placed horizontally above the front vacuum-tanks. It may be double-acting, taking air at one end 70 and compressing air at the other end, the length of stroke to be governed by length of longitudinal motion allowed the car or vehicle body. This air is taken from vacuum-tanks D D through pipe K' and forced thence 75 through pipe k by means of pistons k' k', which operate in said pump K and are shown in Fig. 2 by dotted lines. Said pump K is fastened to the truck-frame, and its piston-rod is attached to a slotted lever Z, which is 80 fastened to the vehicle-platform, the oscillating motion of which actuates the pump-piston. It will be seen that by means of the mechanism described pumps A' A' use the 85 energy of the rolling wheels to actuate them, while pump K uses the energy of the oscillatory motion of the vehicle to actuate it.

When it is desired to ascend a grade or when power is wanted on a level, it is only necessary to open lever-valve M, thus permitting 90 air from high-pressure tanks G G to escape through pipes M' M' and M' M' and thence through pipe N into hollow axle H to any suitable engines in wheels B B, preferably the air or liquid reciprocating engines having 95 a rotary operating mechanism for which I have an application for patent, Serial No. 170,833, pending in the United States Patent Office, the drawings in which application show the engine as applied in this case, thence through 100 pipes D' D' into vacuum-tanks D D, a complete circuit of air having thus been made.

T T are angle check-valves which permit the passage of air, steam, or gas.

T' T' are controlling-valves.

105 P is an automatic relief-valve provided with a rod P', adjustable at will by means of any suitable lever, which is adapted to prevent the pump pulling against a perfect vacuum in tanks D D.

110 R is an emergency-tank, (shown in Fig. 1,) and R' (shown by dotted line) is a flexible

pipe connecting said emergency-tank with high-pressure tanks G G, and r is a relief-valve. The device may be provided with one or more of these emergency-tanks, to be used as occasion may require. The valves f and M are controlled by any suitable levers by means of rod n, which connects them. When valve f is open to tanks G G, valve M is closed; but when going upgrade, and the air is thrown into the engines by means of a three-way valve, valve M is open to tanks G G, and valve f is open to the atmosphere. When going downgrade, the engine-throttle is closed, valve M is open to the atmosphere, and the engines act as pumps exhausting into vacuum-tanks D D. At such time it is immaterial as to whether there is a partial vacuum.

Q represents parts of the frame of the device, and Q' the platform.

Y Y are rollers adapted to travel on the frame in suitable bearings and upon which platform Q' oscillates horizontally as the vehicle is started or stopped, the vehicle being thus assisted in utilizing all its forms of motion.

V V are clamps rigidly attached to the platform and flanged under the frame to aid in holding the platform in position. Being unattached to the frame, these clamps are adapted to a sliding longitudinal motion.

Any ordinary means may be provided for turning the wheels in and out of gear, and any suitable reversing-gear may be attached.

What I claim, and desire to secure by Letters Patent, is—

1. In a vehicle propelled by compressed air, the combination of a truck-frame, the hollow front axle and the wheels carried thereon and the air-pumps in said wheels having a rotary operating mechanism, the duplicate transverse vacuum-tanks and their connecting-pipe, the duplicate high-pressure longitudinal tanks across said vacuum-tanks, the pipes connecting the ends of the vacuum-tanks and said hollow axle and the pumps in said wheels, the transverse pipe and its pipe connections with the front ends of the high-pressure tanks and said axle and their lever and controlling valves, the hollow rear axle, the wheels carried thereon and the engines in said rear wheels having a rotary operating mechanism, the pipes connecting the ends of the rear vacuum-tank and said axle and engines and the check-valves, the rear transverse pipe and its pipe connections with the rear ends of said high-pressure tanks and said axle and their lever and controlling valves and rod, the vertical automatic pumps and their pipes for taking air from said vacuum-tanks and forcing the same into said high-pressure tanks, the automatic relief-valve in the vacuum-tank, the horizontal automatic pump provided with piston and its connections for taking air from the vacuum-tanks

and forcing the same into the high-pressure tanks by means of said pistons, and the emergency-tank and the pipe connection with a high-pressure tank and its circulating-valve, substantially as described and shown. 70

2. In a vehicle propelled by compressed air, the front hollow axle and the wheels carried thereon and the pumps operating therein, the front vacuum-tank for the storage of compressed air, the pipes through which said air is drawn from said tanks into said pumps, the high-pressure tanks and the pipes and valves connecting said pumps and axle and said high-pressure-tanks and through which the air is forced into the high-pressure tanks, 80 the rear axle and the wheels carried thereon and the engines operating in said wheels, the rear vacuum-tank, the pipes and their valves forming connection between said rear axle and the rear ends of said high-pressure tanks 85 and through which air is drawn from said high-pressure tanks and forced into the vacuum-tanks, the pipe connecting the vacuum-tanks and the levers, rods and valves, substantially as set forth and shown. 90

3. In a vehicle propelled by compressed air the rear truck-wheels having engines and the front truck-wheels having pumps adapted to store energy and provided with rotary operating mechanism, the hollow axle upon which said wheels are carried, the vacuum and high-pressure tanks, the rotary vertical pumps and their pipes for drawing air from said vacuum-tanks and forcing it into the high-pressure tanks, the pipes forming connection between said vacuum-tanks and the engines in the rear wheels, said high-pressure tanks and the pipes and valves connecting said axles and high-pressure tanks and the valve-operating lever, the double-acting automatic pump provided with a piston and adapted to take air at one end and compressed air at the other end and its pipe connections with the vacuum and high-pressure tanks substantially as set forth and shown. 105

4. In an air and vacuum motor the combination of the vacuum-tanks, the high-pressure tanks set longitudinally at right angles with and above the vacuum-tanks, the longitudinal automatic pump between said high-pressure tanks provided with a piston, the emergency-tank and the connecting mechanism for carrying air from said vacuum-tanks to the pumps and engines in the wheels of the motor and into and through the high-pressure tanks restoring said air to the vacuum-tanks, substantially as shown and described. 115

5. In an air and vacuum motor, the combination with the connected vacuum-tanks, the front and rear hollow axles, the wheels thereon carrying pumps and engines having rotary operating mechanisms and the pipes extending from the ends of the vacuum-tanks to the ends of the axles to supply air to the pumps and engines, of the high-pressure 125 tanks, substantially as described. 130

tanks set longitudinally with the motor, the front and rear transverse pipes, the pipes connecting the transverse pipes with the front and rear axles, the two lever-valves operated by a single rod, the pipes connected at right angles each at one end with an end of a transverse pipe and each at the other end opening into an end of a high-pressure tank, and the controlling-valves in said pipes, substantially as described and shown.

6. The combination with the frame, axles and wheels provided with pumps and engines therein, the vacuum and high-pressure tanks and the connecting-pipes and valves and levers in an air and vacuum motor, of the vertical automatic pumps at the corners of the

motor, the pipe extending from each of said pumps to a connection with a vacuum-tank through which air may be withdrawn by said pump from said tank, and the pipe extending from each of said pumps to a connection with a high-pressure tank through which said air may be forced by said pump into said high-pressure tank, substantially as set forth and shown.

In testimony whereof I affix my signature in presence of two witnesses.

GEORGE W. JOHNSTON.
